(57) **CLAIM**

The ornamental design for a spraying device, as shown and described.

DESCRIPTION

FIG. 1 depicts a front elevational view of the spraying device according to exemplary embodiments.

FIG. 2 depicts a rear elevational view thereof.

FIG. 3 depicts a side elevational view thereof.

FIG. 4 depicts an opposite side elevational view thereof.

FIG. 5 depicts a top view thereof.

FIG. 6 depicts a bottom view thereof.

FIG. 7 depicts a front elevational view thereof with a selector switch rotated to a second position differing from that of FIG. 1.

FIG. 8 depicts a front elevational thereof with a nozzle portion rotated to a second position differing from that of FIG. 1.

FIG. 9 depicts a top view thereof with the nozzle portion rotated to the position of FIG. 8.

FIG. 10 depicts a bottom view thereof with the nozzle portion rotated to the position of FIG. 8.

FIG. 11 depicts a side perspective view thereof.

FIG. 12 depicts a second perspective view thereof.

FIG. 13 depicts a third perspective view thereof.

FIG. 14 depicts a fourth perspective view thereof.

FIG. 15 depicts a perspective view thereof with the nozzle portion rotated to a second position differing from that of FIG. 1.

FIG. 16 depicts a second perspective view thereof with the nozzle portion rotated to the position of FIG. 15.

FIG. 17 depicts a third perspective view thereof with the nozzle portion rotated to the position of FIG. 15; and, FIG. 18 depicts a fourth perspective view thereof with the nozzle portion rotated to the position of FIG. 15.

The broken lines in the drawings are for illustrative purposes only and form no part of the claimed design.

1 Claim, 18 Drawing Sheets
